DESIGN FOR AN ELECTRIC FLY SWATTER

James P. Foley, Los Angeles, Calif.

Application July 30, 1941, Serial No. 102,566

Term of patent 14 years

To all whom it may concern:

Be it known that I, James P. Foley, a citizen of the United States, residing in Los Angeles, county of Los Angeles, and State of California, have invented a new, original, and ornamental Design for an Electric Fly Swatter, of which the following is a specification, reference being had to the accompanying drawing, forming part thereof.

Fig. 1 is a front elevational view of an electric fly swatter, showing my new design.

Fig. 2 is a side elevational view thereof.

Fig. 3 is an enlarged transverse section taken on the line 3—3 of Fig. 1.

I claim:

The ornamental design for an electric fly swatter, substantially as shown.

JAMES P. FOLEY.
